UNITED STATES PATENT OFFICE.

FRANK T. KOVAR AND JOSEPH F. JIRKA, OF CLEVELAND, OHIO.

SAFETY SWITCH.

Application filed September 12, 1921. Serial No. 499,877.

To all whom it may concern:

Be it known that FRANK T. KOVAR and JOSEPH F. JIRKA, who are residents of the city of Cleveland, county of Cuyahoga, and State of Ohio, and who are citizens of the United States, have invented certain new and useful Improvements in Safety Switches, of which the following is a specification.

10 This invention relates to safety switches and to switch operating mechanism for controlling electric currents of high amperage, though it will be evident that it will be useful for circuits of any description.

15 It is an object of this invention to provide improved and positively operated means for an inclosed type of switch, and especially to render the inclosure safe and uniformly efficient even in the hands of an 20 inexperienced operator. Another object is to provide a construction of this character in which pressure may be applied toward the inclosure either to close or to open the electric circuit, thus making the switch operating means convenient for actuation by the operator's foot. Another object is to provide a hinged cover section for the inclosure which is so related to the switch operating element that the hinged section 25 cannot be raised or lifted without moving the switch to open position, thus preventing closing of the circuits when the contact parts are exposed. A further object is the provision of a switch having a novel form 30 of quick make-and-break operating mechanism by which the switch is both opened and closed with a snap action to avoid a lingering arc.

35 Our invention also resides in certain other features of construction and arrangements of parts which will be described in the specification and set forth in the appended claims. It is, however to be expressly understood that we do not restrict ourselves 40 to this exact disclosure, for we may depart therefrom in many respects within the scope of the invention defined by the claims.

45 In the accompanying drawings which are to be taken as a part of this specification, and in which we have shown merely a preferred form of embodiment of the invention:

Fig. 1 is a top plan view of the switch box and actuating lever.

50 Fig. 2 is a sectional view taken on the line 2—2 of Fig. 1.

Fig. 3 is a section taken on the line 3—3 of Fig. 2.

Fig. 4 is a face view and Fig. 5 an edge view of the rocking lever for actuating the 60 switch bars.

Fig. 6 is a detail view of the telescope plunger and roller.

Fig. 7 is a detail of the bar carrying the 65 switch blades, and:

Figs. 8 and 9 are views of the supporting bracket.

Referring now to the drawings in detail, the numeral 2 designates a base of insulating material, such as slate, which is secured to 70 the bottom of an inclosure which is illustrated as a junction box or panel box 1. This box may be made of sheet metal, though other material may be used. The cover of the box is made in sections one of 75 which, designated 5 is movably secured to a fixed part 4 by hinges 26. Upon the main or fixed part 4 are mounted vertical supporting brackets 6 which are shown as having leaves 31 cut out of the body of the 80 brackets and then bent back from the same and riveted to the box cover (see Figs. 8 and 9). These brackets also are provided with openings at the top and bottom ends to receive the pins 8 and 23 later to be described. The brackets also have slots 25 for a purpose which will later be explained.

The part 4 is provided with a slot 32 on each side edge of which a bracket is mounted. These brackets support the manual operating mechanism which is pivoted to the former by the pin 8 and which mechanism is designed to swing in the slot 32. This mechanism comprises a plunger element 9 and a cross bar 7 secured together by the pin 8. The part 9 which, it has been explained, extends through the slot 32 in the cover comprises telescoping sections 10 which are normally extended to their limit by the force of an internally positioned compression spring 11, and the cross bar is curved and shaped to a form convenient for actuation by pressure applied by the foot or hand at either end of the bar. The pin 8 may well be held against lateral movement by cotter pins as shown. The lower end of the plunger 9 which extends into the interior of the box is formed into a yoke 15 in which is mounted for rotation a roller 14 having an enlarged periphery intermediate its faces 105 for a purpose to be later explained.

The base 2 is provided with binding posts

22 at the ends for connection with conductors to be led into the box through suitable bushings 24. Nearer the end of the box having the hinged cover section the base 5 has suitable clips 20 connected by fuses 21, and the opposite end of the base is provided with spaced switch contacts 19 to be connected by the knife blade switch bars 3 adapted to be raised or lowered to open or 10 close the circuits. Suitable connections are also made between the contact members and between the clips and the posts 22 as will be understood. The blades 3 (2 or more) are mounted on a common insulating block 17 15 having a central opening 18 by which its up and down movements for opening and closing the circuits is guided by a rigid post 16 secured to the base and inserted in said opening.

20 To the block 17 on either side of the aperture 18 are also secured metallic lugs and links by which the operating mechanism may actuate the block and through it the blades. For the latter function an irregular-shaped 25 lever 12 is provided which is pivoted on the brackets 6 by a pin passing through the lower opening 23 of the latter and an intermediate opening 23^a in the lever. This lever is formed of two spaced strips of sheet metal 30 separated at one end to form a yoke 12^a to be connected with the block 17 by the before-mentioned lugs and links, and less widely separated to form a groove throughout the remainder of their length and fixedly se- 35 cured in the parallel relation desired by suitable rivets. One edge of both strips forming the lever is cut out somewhat on either side of the opening 23^a to form notches 13 with an intervening raised portion so that 40 pressure applied at either notch will tip the corresponding end of the lever to a lower position.

This lever 12 is pivoted to the lower or inner portions of the brackets 6 as above de- 45 scribed directly beneath the plunger 9 within the box and is adapted to rock in the same plane that the plunger 9 swings. The roller 14 rides in said groove of the lever and is mounted at such a height that the spring 50 11 will be under compression even when the roller rests in the notches. The enlarged central part of the roller 14 is guided in the groove of the lever 12 while the smaller parts ride on the edges of the lever strips.

55 For the purpose of locking the switch in the "off" position, slots 25 are provided in the outer end of the brackets 6 at the "fuse" side of the pivot 8. A locking strip 27, preferably secured to the box by a chain 29, 60 may be inserted in the slots immediately under the end of the lever 7 when raised to lock the latter in such position.

In operation, assuming that the fuses are 65 in proper position, the block 17 carrying the blades 3 is mounted on the post 16 with the

blades in register with the contacts 19. The plunger element being mounted in position to permit the roller 14 to ride on the lever 12, pressure applied to the lever 7 over the "fuse" end of the box will swing the roller 14 into the notch 13 nearest the post 16 lowering the blades 3 into the contacts 19 and closing the circuits. Such relation of the parts is marked on the box as the "on" position. See the full-line position in Fig. 1. 75 Pressure upon the opposite end of the lever 7 will obviously open the circuits.

In the closed relation of parts, the lower end of the bar 7 is very close to the cover section 5, and for this reason the latter cannot be raised without first moving the switch lever and opening the circuits; and if the hinged section is forcibly lifted, it will automatically shift the switch whether this function is intended or not. This therefore provides a safety element whereby the operator cannot incur the danger of exposing the fuse end of the box while the circuits are closed. 80

85 It will be evident that the disclosed operating mechanism can well be used for operating many kinds of switch elements other than those disclosed herein, and applicants by no means confine this invention to the particular make-and-break means here shown. It will be obvious that a laminated brush of metal leaves may be substituted for the blades 3, in which case the ends would contact with a suitable conducting plate instead of the contacts 19. It will also be evident that the described actuating means for the switch may be advantageously used for operating more than two pairs of bars 3 or for controlling more than one circuit. In fact a number of such switch blades may be mounted on the same block 17. 90 95 100 105

Having thus described our invention, what we claim as new and desire to secure by Letters Patent, is:

1. In a safety switch, an inclosing means for spaced contact points and movable means for bridging the gap between the said points, in combination with a support secured to a fixed cover section of said inclosure and extending above and below said cover, a rocking lever pivoted to the outer end of said support so that pressure applied to either end of said lever will rock the same, there being slots in said outer end immediately beneath one end of said lever, a locking bar adapted to be inserted in said slots to prevent the actuation of said lever, and means including a part pivoted to the inner portion of said support, connected with said lever for actuating the said bridging means. 110 115 120 125

2. In a safety switch, a support for spaced contact members, an inclosing means for said members and movable means for bridging the gap between said members to close a circuit, in combination with a support 130

bracket secured to a fixed part of said inclosing means, said bracket extending within and outwardly from said inclosing means, a movable cover section for said inclosure, a 5 rocking lever pivoted to the outward end of said bracket so that pressure applied to either end of said lever will rock the same, means connected with said lever, including a part mounted on the inner part of said 10 bracket for actuating the said bridging means, said movable cover section being hinged directly beneath one end of the rocking lever, so that the closure of the switch is prevented when the box is open, and the 15 moving of the cover section to open the box will automatically open the switch.

3. A safety switch comprising a movable insulating bar carrying electrical conducting members for bridging the gap between 20 spaced contact elements to close a circuit, an inclosure for said bar and conducting members, having fixed and movable cover sections, in combination with a pair of support brackets spaced apart in parallelism and 25 having leaves cut out thereof and bent back therefrom and riveted to said fixed cover section to mount said brackets to extend outside the box and within the same, a pivoted operating lever mounted on the 30 outer extension so that the lever will rock by the application of pressure to either end thereof, the movable cover section being hinged directly beneath one end of the rocking lever so that opening the said hinged 35 section will rock the lever if said end of the latter is down, means for locking the lever when said end is raised, and means mounted on the inner extensions of said brackets for actuating the said bar by rocking the lever.

4. A safety switch comprising, an insulating support for spaced contact points, means for bridging the gap between said points and an inclosing means for said support and its related structure, including a cover having 45 fixed and movable sections, a lever pivotally mounted on said fixed cover section but within the inclosure, and having connections at one end with said bridging means for actuating the latter and notches 50 adjacent its other end on opposite sides of its pivot, in combination with a pivoted operating lever mounted on the outer face of said fixed cover section, so that it will rock by the application of pressure to either 55 end thereof, actuating means for said notched lever, connected with said pressure-actuated lever and including a swinging plunger element carrying a roller for engaging 60 said notched lever and seating in said notches, selectively, said movable cover section being hinged directly beneath one end of the rocking lever, so that opening said hinged section will rock the lever, if the adjacent end of the lever is down and thereby 65 open the switch.

5. A safety switch comprising a switch box having a support for fuse terminals and both power and load conductors, and a sectional cover, a switch arranged to connect and disconnect said fuse terminals with said conductors, a lever pivoted to a fixed section of said cover and having connections at one end with opening and closing elements of said switch and notches at the other end thereof situated on either side of the pivot for said lever, a spring-pressed plunger pivoted on the outer face of said fixed cover section and having a roller on one end thereof for engaging the said notches selectively, and manual operating means on the outer face of said cover section for actuating the said plunger to open or to close the circuit, said means being operable for either purpose by pressure applied in a direction toward the said support. 70

6. A safety switch comprising in combination, a fixed post for guiding the vertical movement of electrical conducting members for bridging the gap between spaced contact elements when said members are in the down position, a fixed vertical supporting member positioned above said elements, a swinging lever pivoted on the lower end of said supporting member and having connections with said members at one end and a pair of connected notches at the other end, the pivotal point of the lever being between the notches so that pressure applied at either notch will lower the corresponding end of the lever to raise or lower the said conducting members and thereby open or bridge the said gap, and actuating means including a plunger pivoted on the upper end of said supporting member manually operable by pressure thereon at spaced portions thereof for applying pressure to the respective notches selectively. 80

7. In combination, a switch base of insulating material, an elongated support fixed relative to and at an angle to the plane of said base, spaced contacts on said base, conducting elements mounted for movement to and from said contacts, a lever pivoted to the lower end of said support and having connections with said conducting elements at one end and notches adjacent the other end on opposite sides of the fulcrum, a plunger element having a cross bar fixedly secured to one of its ends and a roller rotatably mounted on the other end, the said plunger element being mounted on the upper end of said support for swinging movement above said pivoted lever so that said roller may engage one of said notches in said lever, and follow the contour of the edge of the lever as it passes from one notch to the other during the swinging movement of the plunger element. 90

8. In a safety switch, an inclosing means for spaced contact points and movable means 100

105

110

115

120

125

130

for bridging the gap between the said points, in combination with a support, a cover for said inclosure having fixed and hinged sections, said support extending above and below said cover and secured to the said fixed section, a rocking lever pivoted to the outer end of said support so that pressure applied toward the cover at either end of said lever will rock the same, means mounted on the lower extension of said support for actuating said bridging means and having operat-

ing connections with said rocking lever, the said hinged cover section being directly beneath one end of the said lever so that opening said hinged section will rock the lever, if the adjacent end of the lever is down and thereby open the switch. ¹⁵

In testimony whereof we hereunto affix our signatures.

FRANK T. KOVAR.
JOSEPH F. JIRKA.
